C. A. LEWIS

SENTINEL FOR WINDOW SASHES

Filed Jan. 22, 1927

FIG. 1

FIG. 2

FIG. 3

Claude Alexander Lewis

INVENTOR.

BY *Jesse R. Stone*

ATTORNEY.

UNITED STATES PATENT OFFICE.

CLAUDE ALEXANDER LEWIS, OF HOUSTON, TEXAS, ASSIGNOR TO AMERICAN WINDOW COMPANY, OF HOUSTON, TEXAS, A CORPORATION OF DELAWARE.

SENTINEL FOR WINDOW SASHES.

Application filed January 22, 1927. Serial No. 162,722.

My invention pertains to windows and particularly windows wherein the sash is mounted to swing inwardly at the upper end on a pivot provided adjacent its lower end. 5
5 In handling windows wherein the sash is thus pivoted at the lower end so that the upper end may swing into the room toward the operator, it may at times occur that the sash is not carefully handled so that it slips 10 from the grip of the operator and falls downwardly, injuring the window and perhaps the operator. This is sometimes the case even where a guard is provided to prevent accident of this kind. 15
15 It is an object of the invention to provide a guard or sentinel which will automatically obstruct the falling of the sash in this manner. It is intended that the said sentinel may also act as a support for 20 the sash when it is moved inwardly to provide a vent at the upper end.

Referring to the drawing herewith, Fig. 1 is a section through a window casing at one side of the upper sash and showing my 25 invention applied to said casing. Fig. 2 is a broken front elevation of said window casing and sash and further illustrating my attachment, and Fig. 3 is a front view of a portion of the casing illustrating the sentinel thrown into inoperative position.

My invention is adapted to be applied to all types of windows having a swinging sash. I have shown the same as applied to an ordinary wooden window frame and sash, it being understood that the invention is applicable to any ordinary type of window. With reference to the drawings, the casing is shown as including an inner frame member 1 surrounding the window opening. 40 To the rear of this frame member is a stop plate 2 extending inwardly from the frame member to provide means to limit the outward movement of the sash 3 therein. Outside of the stop member 2 is the usual 45 facing member 5. On the inner side of the casing a frame member 6 extending around the window opening is of slightly larger internal dimension from the frame or jamb member 1, to provide a shoulder at 7. 50 The sash 3 is adapted to be pivoted adjacent its lower end upon laterally extend-

ing pins 8 which project into recesses or sockets 9 in the window jamb and allow the upper end of the sash to be swung inwardly into the room. Its movement outwardly 55 is limited by the stop member 2.

The sentinel which I have devised to act as a stop to prevent the accidental falling of the sash when it is swung inwardly comprises a flat plate 10 of sheet metal or 60 the like, which may be mounted within the window casing and preferably on the forward face of the window jamb and set within a recess 11 in the shoulder 7. The plate 10 has an inwardly extending arm 12 at its 65 upper end adapted to fit within the recess 11 and is pivotally supported therein by a pin or screw 13 secured in the face of the window jamb. A similar recess 11' spaced downwardly from the upper recess is formed 70 in the shoulder 7 to receive a lower arm 14, said arm being formed at the lower end of the plate and extending inwardly toward the sash sufficiently to project within the path 75 of the sash when it is swung on its pivot. The projecting end of said arm is extended upwardly and bent forwardly into the room to provide a rounded contact finger 15 against which the sash may strike. Above the lower arm 14 the plate 10 may be formed 80 with a short arm 16 which will normally contact with the outer side of the frame of the window and limit the inward swinging of the sentinel. It will be noted that with the plate pivoted at the point 13, the center 85 of gravity is slightly inside of the vertical line below said screw 13, thus tending to throw the arm 14 inwardly in front of the sash. The movement of said arm inwardly is limited, however, by the stop arm 16 so 90 that the sentinel will ordinarily hang in the position shown in Fig. 2.

When the sash is swung inwardly on its lower pivot, it will strike the arm 14 and will be prevented from swinging beyond 95 that point, which is shown in Fig. 1 in dotted lines, until the arm 14 has been moved laterally away from in front of the sash. This may be easily done by the operator who grasps the sash at approximately the height 100 of the arm 14 and supports the sash and at the same time moves the arm 14 laterally

away from in front of the sash, as shown in Fig. 3, thus allowing the sash to move forwardly. In this position, the danger of the sash dropping thereafter is practically nil and accidents will be readily avoided.

When the sash is to be swung back into its vertical position, it will contact with the rounded lower side 17 of the arm 14 automatically forcing it into the Fig. 3 position 10 and allowing the sash to be swung upwardly. It may be secured in its closed vertical position in any manner desired, but as such a means is not a part of my invention, no latch is shown.

15 It will be obvious that my invention will prevent accidental swinging of the sash beyond a position where it may be properly supported by the operator. If it is desired to provide a vent at the upper end of the 20 sash, said sash may be swung into contact with the stop arm 14, as shown in the dotted line position of Fig. 1, and a sufficient vent for ordinary purposes will be provided with the sash in that position. The sentinel 25 will not, however, prevent the reversing of the sash to obtain access to the outer side of the window pane in the manner already described.

Having thus described my invention, what 30 I claim as new and desire to protect by Letters Patent is:

1. In a window having a sash adapted to swing on pivots adjacent its lower end, the combination of a stop arm mounted in the 35 window frame and pivoted to swing by gravity to a position in the path of the said sash when said sash is swung on its pivots.

2. In a window having a sash adapted to

swing on pivots adjacent its lower end, the combination of a sentinel comprising a plate 40 mounted in the window frame and having a laterally extending arm, said plate being pivoted to swing by gravity to a position in the path of the said sash when said sash is swung on its pivots.

45 3. In a window having a frame and a sash pivoted adjacent its lower end in said frame, the combination of a sentinel comprising a plate supported on said frame, an arm on said plate projecting into the path 50 of said sash when said sash is swung on its pivots, and a contact finger on said arm to contact with and support said sash.

4. In a window having a frame and a sash pivoted adjacent its lower end in said frame, the combination of a sentinel comprising a plate supported on said frame, an arm on said plate projecting into the path 55 of said sash when said sash is swung on its pivots, and a contact finger on said arm to contact with and support said sash, the lower side of said arm being curved so that 60 said arm will be automatically forced back from said sash when said sash is swung upwardly in said frame.

65 5. In a window having a frame and a sash pivoted adjacent its lower end in said frame, the combination of an arm on said frame adapted to be held by gravity in a position 70 in the path of said sash and means to limit the inward movement of said arm.

In testimony whereof I hereunto affix my signature this 13 day of January, A. D. 1927.

CLAUDE ALEXANDER LEWIS.
